UNITED STATES PATENT OFFICE.

EDWARD A. TUTTLE, OF MORRISTOWN, NEW JERSEY.

DESIGN FOR A HOT-AIR REGISTER.

Specification forming part of Design No. 6,645, dated May 6, 1873; application filed April 19, 1873.

To all whom it may concern:

Be it known that I, EDWARD A. TUTTLE, of Morristown, in the county of Morris and State of New Jersey, have invented a new and Improved Design for Register for Hot Air and other Purposes, of which the following is a specification:

The nature of this design is fully represented in the accompanying illustration, to which reference is made.

The plain border *a* describes a figure rectangular at the bottom and circular at the top. A series of curved and straight bars, *b*, are joined and arranged within said border to form an irregular figure approximating a lyre in shape, and the space between it and the border

is filled with lattice-work *c*. The center of this figure is occupied by a vertical figure somewhat analogous to an ordinary flower-vase, with enlarged base or body and oval-shaped top. Intertwined with the curved cross-base *e*, forming this latter figure, and also joining the bars *b*, is a series of arabesques, *f*. A representation of a rail-car, *d*, is placed at the bottom of the design next the border *a*.

I claim as my invention—

The design for a register, substantially as set forth.
